E. K. BOTTLE.
MANIFOLDING SALES BOOK.
APPLICATION FILED JUNE 28, 1912.

1,160,248.

Patented Nov. 16, 1915.

UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, CANADA, A CORPORATION OF ONTARIO.

MANIFOLDING SALES-BOOK.

1,160,248.

Specification of Letters Patent   Patented Nov. 16, 1915.

Application filed June 28, 1912. Serial No. 706,313.

To all whom it may concern:

Be it known that I, EDWARD KIRBY BOTTLE, a citizen of the United States, residing at Elmira, in the county of Chemung and State 5 of New York, have invented certain new and useful Improvements in Manifolding Sales-Books, of which the following is a full, clear, and exact description, such as will enable others skilled in the art to which it applies 10 pertains to make and use the same.

This invention relates to manifolding sales books and with regard to certain more specific features thereof, to waiters' check books adapted for use in cafés, hotels and 15 the like.

My present invention relates to manifolding sales books of well known form, and to adapt it to the uses above suggested, I arrange a pad of duplicates and beneath it, 20 but separated from it by a part of the holder which may be moved about the usual flexible part of the binding as a hinge, is a pad of originals attached at their upper ends so that one of the originals may be withdrawn 25 and raised up so as to lie upon the pad of duplicates, the usual carbon sheet being interposed between them. For the purposes to which this book is usually applied, the duplicates are somewhat wider than the 30 originals and this excess width is arranged upon the right-hand side. A guide rod or wire is pressed down by a spring so as to hold the original in place and this wire extends vertically down the face of the duplicate. In combination with this arrangement 35 I employ a stamp having duplicate figures upon its face, and positioning means consisting of the wire or rod just referred to and a suitable groove upon the face of the 40 stamp, are provided, by means of which it is possible to insure the alinement of figures so that the stamp may be used to impress them simultaneously upon the original and upon the duplicate. There are other details 45 in connection with the invention which will be apparent from the drawing and description which I aim to cover by the claims.

In the accompanying drawing wherein is shown one of the various possible embodiments of this invention, Figure 1 is a perspective view of the complete device in operative position. Fig. 2 is a side elevation

of the device in the position shown in Fig. 1. Fig. 3 is a perspective view of a stamp designed to be used in connection with this 55 form of salesbook. Fig. 4 is a detail.

Similar reference characters refer to similar parts throughout the several views of the drawing.

Referring now to the drawing in detail, 60 the salesbook as shown in Fig. 1 is provided with a rear cover 1 and a top cover 2 connected by means of a flexible hinge 3. The bottom cover 1 is provided at its opposite end with a second flexible connection, or 65 hinge 4, to which is secured a back 5. Removably mounted upon the rear cover 1 is a pad 6 of original leaves which are bound together along one end by means of staples 7. Weakening lines of perforations 9 separating the body portions of the leaves from their stub portions 8 are provided whereby the leaves may be readily detached from the pad. This pad normally rests beneath the back 5. Removably mounted upon the 70 back 5 is a second pad of duplicate leaves 10 bound together by means of staples 11; the parts of the leaves remaining attached are shown at 12. These leaves are also provided with weakening lines 13 to permit of ready 75 detachment. This pad of duplicate leaves 10 has also bound therewith a carbon sheet 14 which normally rests over the larger part of the top duplicate leaf and is of a width equal to the width of the top original leaf 80 placed thereover when the book is in operative position. Hinged to one side of the back 5 at a point 15 is an L-shaped wire 85 guide 16 which extends across and over the top leaf of the original pad and thence 90 downwardly along the right hand edge of the original leaf when the book is held in operative position as shown in Fig. 1. The upper right hand corner of the duplicate pad is cut away to the full depth of the pad 95 as indicated at 17 whereby as the leaves of the pad are torn off the guide 16 is permitted to pass down into the cut away portion to rest upon the top duplicate leaf.

Fig. 4 is a detail perspective of the upper 100 right-hand portion of the pads taken in the direction of the arrow 4 upon Fig. 1, which renders more clear the cut through which the wire 16 passes. Reference characters 22,

23 show respectively the pasteboard backings of the pads of originals and duplicates of the upper right-hand portion of the pads.

As above stated, the present book is particularly adapted for use in cafés and hotels where after a waiter has received an order and before serving the same is obliged to pass a checker who stamps upon the bill the price of each article served. As the stamp will not readily make an impression through a carbon sheet it would be necessary to stamp both the original and duplicates separately. In the present device, however, a stamp 18 such as shown in Fig. 3, which is only one of a set, is provided with a notch 19 adapted to fit or straddle the wire guide 16 between duplicate characters 20. It will thus be seen that unless the wire enters the notch 19 the stamp cannot coat with the leaves, but when in proper position the character upon one side of the notch will make its impression upon one of the leaves while the character upon the opposite side will make a corresponding impression upon the other leaf, thus the impressions may be made more easily and quickly and in a manner which will prevent their being changed without detection.

As it frequently happens a waiter is serving more than one table at a time and as additional orders may be made before the guest receives his check it is necessary for the waiter to detach the top set of leaves while serving another guest. A spring clip 21 is provided upon the cover 2 under which the detached set of leaves 22 may be slipped and be firmly held until the waiter reaches the kitchen or departments where the checks are deposited.

Having described the general construction of one form of the invention, the operation thereof is substantially as follows:— Assuming the book to be in position shown in Fig. 1, the waiter writes upon the original leaf the names of the various dishes ordered and when ready to serve presents the entire book to the checker who being familiar with the prices of the dishes simultaneously stamps the proper amount in duplicate after each order by means of stamps such as shown in Fig. 3. These prices appear in two parallel columns, one upon the original leaf and the other upon the duplicate leaf at opposite sides of the guide 16. If the waiter is called to wait upon another table he removes the original and duplicate leaves from the respective pads and places them beneath the clip 21. The back 5 with the duplicate pad is swung upwardly to permit access to the next original leaf on the pad normally positioned therebeneath as shown in Fig. 2. This leaf is withdrawn from beneath the back 5 and then laid over the duplicate pad and the wire arm 16 placed in position thereover,

thus holding the original leaf in place as clearly shown in Fig. 1. The book is then ready for subsequent operations.

It is thus seen that this invention provides a simple and practical device which may be easily manipulated and adapted to accomplish, among others, all the objects and advantages above set forth.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a manifolding sales book, the combination of a pad of duplicates, a pad of originals beneath the duplicates, the duplicates being wider than the originals, supporting means for the pads, such means permitting the duplicates to be lifted so that an original may be disposed upon the top of the duplicates, a stamp having duplicate characters arranged to print both upon the duplicates and the originals, and positioning means for the stamp whereby the alignment of its characters with entries which may be made upon the original and duplicate is assured.

2. In a manifolding sales book, in combination, an original pad, a duplicate pad normally positioned beneath the top leaf of the original pad, manifolding means associated with one of the pads whereby records of the transaction may be made in duplicate, said duplicate pad being wider than the original pad whereby the prices of the articles ordered may be stamped simultaneously upon the leaves of both pads in parallel columns, and movable means for holding the original leaf in operative relation to said duplicate leaf.

3. In a manifolding sales book, in combination, an original pad, a duplicate pad normally positioned beneath the top leaf of the original pad, manifolding means connected with one of the pads whereby records of the transaction may be made in duplicate, said duplicate pad projecting to one side of the original pad whereby the prices of the articles ordered may be stamped simultaneously upon the leaves of both pads in parallel columns, and means for insuring the stampings to be made in proper position.

4. In a manifolding sales book, in combination, an original pad and a duplicate pad normally positioned thereover and beneath the top leaf of said original pad, manifolding means between the leaves of

- the top set, the duplicate pad projecting to one side of the original pad to form a column in which the prices of the articles ordered may be stamped, a stamp having two sets of characters thereon adapted to simultaneously record prices of the articles ordered upon both leaves, and means for maintaining the alinement of the stamped impressions.
- 10 5. In a manifolding sales book, in combination, a holder, an original pad, a duplicate pad normally positioned thereover and beneath the top leaf of said original pad, manifolding means between the leaves of
- 15 the top set, the duplicate pad projecting to one side of the original pad to form a column in which the prices of the articles ordered may be stamped, a stamp having two sets of characters thereon adapted to simultaneously record prices of the articles ordered upon both leaves, and a wire connected with one of said parts extending along the edge of the original leaf adapted to engage a notch in the stamp whereby the
- 20 25 stamped impressions are made in proper alinement.
6. In a manifolding sales book, in combination, a holder, a back flexibly connected with said holder, an original pad mounted upon the holder, a duplicate pad extending to one side of the original pad mounted upon said back, a guide member connected with one of said parts extending along the edge of the original pad adjacent the projecting side of the duplicate pad, and a stamp having a notch therein coacting with the guide member whereby the prices of the
- 30 35 articles ordered may be simultaneously stamped in parallel columns upon both leaves.
7. In a manifolding sales book, in combination, an original pad, a duplicate pad normally positioned beneath the top leaf of the original pad, a guide arm for a stamp attached to one of said pads, said duplicate pad having a cut-away portion in the stub portions of the leaves into which the guide arm falls as the leaves thereof are detached.
8. In a manifolding sales book, in combination, an original pad, and a duplicate pad normally positioned beneath the top leaf thereof, a carbon sheet bound with the leaves of the duplicate pad and normally positioned between the leaves of the top set, said duplicate pad extending to one side of the original pad and having a cut-away portion in the stub portions of the leaves thereof, a guide arm connected with said duplicate pad and extending through said cut-away portion and longitudinally of the duplicate pad and adjacent the edge of the original leaf, and a stamp having duplicate characters thereon and a cut-away portion therebetween adapted to engage the guide arm whereby the prices of the articles ordered may be simultaneously stamped upon both leaves.

In testimony whereof I affix my signature, in the presence of two witnesses.

EDWARD KIRBY BOTTLE.

A. L. GENTHER,
PHILIP LAPPLA.

Copies of this patent may be obtained for five cents each, by addressing the "Commissioner of Patents, Washington, D. C."

It is hereby certified that in Letters Patent No. 1,160,248, granted November 16, 1915, upon the application of Edward Kirby Bottle, of Elmira, New York, for an improvement in "Manifolding Sales-Books," errors appear in the printed specification requiring correction as follows: Page 1, line 56, for "Fig. 4 is a detail." read *Fig. 4 is a perspective detail of the upper right hand portion of the pads.*; same page, line 100, strike out the word "detail"; page 2, line 2, after the word "duplicates" strike out the word "of" and insert a period; same page, strike out line 3; and that the said Letters Patent should be read with these corrections therein that the same may conform to the record of the case in the Patent Office.

Signed and sealed this 11th day of January, A. D., 1916.

[SEAL.]

J. T. NEWTON,
Acting Commissioner of Patents.
